UNITED STATES PATENT OFFICE.

JACOB T. SHIMER, OF SOUTH BETHLEHEM, PENNSYLVANIA, ASSIGNOR TO
A. R. SHIMER, OF SAME PLACE.

COPING FOR FENCES.

SPECIFICATION forming part of Letters Patent No. 432,000, dated July 8, 1890.

Application filed April 9, 1890. Serial No. 347,225. (No model.)

To all whom it may concern:

Be it known that I, JACOB T. SHIMER, a citizen of the United States, residing at South Bethlehem, in the county of Northampton and State of Pennsylvania, have invented certain new and useful Improvements in Copings for Fences, &c., of which the following is a specification, reference being had therein to the accompanying drawings, in which—

10 Figure 1 represents a side elevation of my improved coping employed to support a fence; Fig. 2, a transverse sectional view of the same; Fig. 3, an enlarged side elevation of one section of the coping; and Fig. 4, a detail horizontal sectional view showing another manner of attaching the side plates to their supports.

The essential object of this invention is to obviate the use of the ordinary stone and wooden basings or copings now employed to support fences and the like and substitute in lieu thereof an extremely cheap and light metallic coping, which will not only be more durable and rigid than the old styles of coping, but which will also be more pleasing and neater in appearance, as will more fully hereinafter appear.

The invention consists in certain novel features of construction and combination of parts, that will fully hereinafter appear, and be particularly pointed out in the claim appended.

In the drawings, *a* designates the metallic posts or supports of the coping, which consist of plates of the same width as the coping and sufficiently long to extend into the earth far enough firmly to anchor the same. The lower buried portions may be provided with slots or openings *a'*, if desired, to assist in firmly anchoring them, and they may also be embedded in cement or other plastic compound if it is desired to establish them more firmly. The edges of each post above the surface of the ground are provided with integral flanges *a''*, which are set at right angles to the plate

and are in line with its edges, as shown. These flanges project from both sides of the plates and afford means of attachment for the metallic side plates *b* and the top plates *b'* of the coping. The coping-plates are secured to the flanges of the supports by screws, as shown in Fig. 3, or by keys, as shown in Fig. 2, or by lugs formed on the inner sides of the plates and adapted to embrace the flanges on the supports, as shown in Fig. 4. The supports are placed at suitable intervals along the line of the fence, preferably at the joints of the side and top plates, as shown. The lower edges of the side plates are preferably about 50 on a level with the surface of the ground, and the top plates may be beveled off or inclined in order to shed the water readily and prevent its collecting on top of the coping. These plates may be ornamented in any suitable manner.

This coping may be used for other purposes than supporting fences, as is evident, without departing from the invention. In fact, it may be employed by itself where an ornamental and durable border is desired. For instance, it may be employed as borders for cemetery-lots or ornamental walks, and for analogous purposes.

Having thus described my invention, what I claim, and desire to secure by Letters Patent, is—

In a metallic fence-coping, the combination of the posts *a*, provided with oppositely-projecting flanges *a''* and adapted to be inserted in the ground, and the side and top plates *b* *b'*, secured to the portions of the said flanges projecting above the surface of the ground, substantially as described.

In testimony whereof I affix my signature in presence of two witnesses.

JACOB T. SHIMER.
